PERCUSSIVE TOOL

William Henry Dean, Darlington, England

Application June 20, 1945, Serial No. 600,495
In Great Britain June 26, 1944

3 Claims. (Cl. 125—33)

1

This invention relates to percussive tools, and is applicable to percussive tools actuated by a resilient medium, for example, by pneumatic power or by power resulting from the alternate contraction and expansion of a spring. In the latter case, the power may originate in reciprocating mechanism apart from said tool coupled thereto by a flexible connection. My invention is especially applicable to riveting tools and to chisels for drilling holes in brickwork and the like.

One object of my invention is to provide a power-operated percussive tool with means whereby the application of power to the tool is automatically controlled as the tool is applied to and removed from the work.

A further object is to provide, in combination with said tool, improved power-driven reciprocating mechanism and an improved flexible drive whereby the reciprocations of said mechanism are transmitted to the tool.

With these and other objects in view, my invention consists of the novel features of construction herein described and illustrated and specifically set out in the appended claims.

I will fully describe my invention with reference to the accompanying drawings wherein

Figure 1 is a longitudinal section of one construction of tool in accordance with my invention fitted with a riveting set, the working parts of the tool being shown in their operative positions;

Figure 2 is a section on the line II—II in Fig. 1;

Figure 3 is a part similar view to Fig. 1 showing the working parts of the tool in their inoperative positions; and

Figure 4 is a section on the line IV—IV in Fig. 3.

Figure 5 is a view looking on the right-hand end of Fig. 1, and

Figure 6 is an elevation of a chisel with its holder and tommy-bar which can be substituted for the rivet set of Figs. 1 and 3.

Figure 7 is an elevation of a power-driven reciprocating mechanism and flexible transmission (the latter in section) suitable for actuating the tool illustrated in Figs. 1 to 5, the cover of the casing of the mechanism being removed for clearness and the working parts thereof being shown in positions corresponding to those of the working parts of Figs. 1 and 2;

Figure 8 is a plan section on the line VIII—VIII in Fig. 7; and

Figure 9 is a similar view to Fig. 7 showing the working parts of the reciprocating mecha-

2

nism in positions corresponding to those of the working parts of Figs. 3 and 4.

Referring to Figs. 1 to 5 of the drawings, in the riveting tool therein illustrated, 10 is a piston reciprocating in a cylindrical barrel 11 and having at its forward end and integral with it a hammer 12 which coacts with the tapered rear end 13 of a work-engaging member, such for instance as a cylindrical rivet set 14, the forward portion 15 of which projects through the nose 16 of a working head 17. The latter is hollow and contains within it a cylindrical block 18 which is free to slide in a direction perpendicular to the longitudinal axis of the tool and is pressed out of concentricity with said axis by a ball 19 on which bears a spring 20 provided in a socket 21 in the working head closed by a screwed plug 22. Into the rear end of the working head 17 a flanged cover 23 is screwed, said cover being provided with a central hole 24 through which the forward end of the hammer 12 enters the working head. The block 18 is provided with a central socket 25 tapered to correspond with the rear end 13 of the rivet set, and said block is also provided with a central aperture 26 of diameter slightly greater than that of the hammer 12. 27 is a ring for locking the cover 23 on the forward end of the barrel 11 and so securing the working head 17 thereon.

30 A spring 28 is disposed between the nose 16 of the working head and a washer 29 on the forward portion 15 of the rivet set coacting with a securing pin 30 therein, said spring serving to maintain the rivet set in its fully projected position when not in use. When the rivet set is in its fully projected position, its tapered rear end 13 is clear of the tapered socket 25 in the block 18, and, on the hammer 12 being retracted to the rearmost extremity of its stroke, the forward end of the hammer is clear of the aperture 26 in the block though still projecting into the hole 24 in the cover 23. The disengagement of the rivet set and of the hammer from the block 18 allows the block, under the pressure of the spring 28 and ball 19 to move into an eccentric position in relation to the axis of the tool, as shown in Figs. 3 and 4. In this position, the blows of the hammer 12 are absorbed by the block 18 and the working head 17, the face of the hammer merely chattering against the margin of the aperture 26 in the block.

When however the forward end 15 of the rivet set is applied with pressure to a rivet (indicated in dotted lines at 31 in Fig. 1), the rivet set is pressed in against the spring 28 and its tapered

rear end 13 enters the socket 25 in the block 18 and, against the action of the spring 20, forces said block into the position shown in Figs. 1 and 2 in which its axis is concentric with the axis of the tool and its aperture 26 registers with the hole 24 and the hammer 12. This movement of the block 18 permits the hammer to reciprocate through the hole 24 and aperture 26 and strike the opposed face of the rivet set thereby imparting the percussive blows of the hammer through the rivet set to the rivet 31. The action persists so long as the forward end of the rivet set 14 is pressed against the rivet 31, but relief of rearward axial pressure on the rivet set immediately permits projection thereof by the spring 28 whereupon the rivet set disengages the socket 25 and the block resumes its eccentric position.

It will be understood that a chisel, such as that illustrated at 32 in Fig. 6, may be substituted for the rivet set 14, the shank 33 of said chisel being received in a socket 34 in a tool-holder 35 provided with a tapered rear end 36 identical with the rear end 13 of the rivet set 14 and operating in similar manner in the working head 11. In place of the pin 39 co-acting with the spring-pressed washer 29 of Fig. 1, a tommy-bar 37 of suitable length is screwed into a tapped hole 38 in a widened washer 39 on the tool-holder 35, the end of said bar projecting through a hole 40 in said holder and abutting against a flat 41 on the shank 33 of the chisel thus securing the chisel and enabling it to be rotated during the drilling operation. The washer 39 also forms the bearing surface for the forward end of the spring 28 on the nose 16 of the working head shown in Figs. 1 and 3.

It may be preferable that the working head 11, complete with its nose 16, rivet set 14, washer 29, spring 28, block 18, plug 22, spring 20, ball 19 and flanged cover 23, shall be manufactured as a sealed assemblage which can be screwed as a unit onto the forward end of the barrel 11 of the tool and locked thereon by the ring 27, and that the chisel 32 shall be incorporated in a similar sealed assemblage which can be substituted as a unit for the rivet set carrying working head of Figs. 1 to 5.

The piston 10 may be reciprocated in the barrel 11 of the tool by any suitable power-driven mechanism. The arrangement illustrated in the drawings herewith is the preferred method of actuating the tool and comprises a quick-return reciprocating mechanism hereinafter more particularly described, mounted within a casing 42, Figs. 7, 8 and 9, and coupled by a flexible cable 43 with a non-reciprocatory flexible sheath 44 to the rear end of the piston 10.

The forward end of the cable 43 is provided with a spherical-headed nipple 45 engaged in a slot 46 in the rear end of the piston 10, said cable passing through a flanged bush 47 in an externally-threaded flanged sleeve 48 projecting into the barrel 11 of the tool. The sleeve 48 is screwed into the rear end 49 of the barrel 11 and into the centre portion 50 of a handle 51 positioned to provide a balanced support for the tool. A powerful helical compression spring 52 extends between the rear end 49 of the barrel 11 and the rear end of the piston 10. The bush 47 forms a socket for the forward end of the sheath 44 which is retained in the rear end of the sleeve 48 by a terminal 53 provided on the end of a flexible tube 54, said tube, adjacent to the handle 51, being provided with a guard spring 55 the forward end of which engages in a helical

groove around the rear end of the flanged sleeve 48 as shown in Fig. 1, said rear end and the guard spring being enclosed in a socket 56 in the rear end of the handle 51 of the tool.

In operation, the stroke of the piston 10 towards the right under the pull of the cable 43 compresses the helical spring 52 and completely withdraws the hammer 12 from the aperture 26 in the block 18 into the position indicated in Fig. 10. The stroke of the piston towards the left is the operative stroke wherein the piston is projected by its spring 52 until the hammer 12 strikes the rear end 13 of the rivet set, provided that said rivet set is pressed against the work and its rear end engages sufficiently in the tapered socket 25 in the block 18 to retain the axis of said block concentric with the axis of the tool as shown in Fig. 1. If the rivet set is not pressed against the work, it is projected by its spring 28 and its rear end is disengaged from the block 18 which automatically assumes the position shown in Figs. 3 and 4, subsequent blows of the hammer being taken by the rear face of the block 18, the blows then occurring being only minute.

Referring now to the quick-return reciprocating mechanism shown in Figs. 7, 8 and 9, 57 is the shaft of a suitably supported electric motor (not shown), said shaft projecting through an oil seal 58 in the rear wall 59 of the casing 42. The side walls of the casing are flanged as shown at 60 and a removable cover 61 (Fig. 8) is attached to said flanges by screws (not shown) disposed at intervals around the flanges. The casing is thus made oiltight and is partly or wholly filled with liquid lubricant through an aperture 62 in the top wall 63 of the casing normally closed by a screw-in plug 64. A flywheel 65 is screwed onto the end of the motor shaft 57 within the casing, said flywheel being provided with an eccentric driving pin 66 which coacts with the under face 67 of a lever 68 pivoted on a fulcrum pin 69 provided within the bottom of the casing. The lever 68 has a pin 70 projecting from its side which engages a link 71 having parallel sides 45 united by rounded ends, its right-hand end being slotted at 72 to receive the shank 73 of a spherical-headed nipple 74 on the opposite end of the cable 43 to the nipple 45 in the piston 10 of the tool. The pin 70 is connected by a helical tension spring 75 to the end of a stationary support 76 in the bottom of the casing 42 remote from the fulcrum pin 69, said spring maintaining the under face 67 of the lever 68 constantly against the eccentric pin 66 of the flywheel 65. The extreme positions of the pin 66, lever 68, pin 70 and nipple 74 are shown in Figs. 7 and 9 respectively, said positions corresponding to those of the working parts of the tool as shown in Figs. 1 and 2 and in Figs. 3 and 4 respectively.

The cable 43 passes through a threaded bush 77 screwed into the lower right-hand end of the casing 42, said bush being flanged at 78 and fitted with a tubular sleeve 79 carrying a nipple 80 suitable for the application of the nozzle of a lubricant gun. Oil or light grease forced into said nipple passes through a port 81, an annular space 82 and a port 83 into a space 84 around the end of the flexible sheath 44 which is received in a socket 85 in the bush 77, said bush being screwed onto the terminal 86 of the flexible tube 54 within which the sheathed cable 43 is contained. The end of a helical guard spring 87 engages a helical groove around the bush 77 beyond its flange 78 and encloses the

flexible tube 54 for a short distance from the casing 42.

The position of the piston 10 in the barrel 11 can be adjusted, by holding said barrel firmly by the working head 17 and slightly rotating the handle 51 which serves as a locking nut on the thread of the sleeve 48 within the centre portion of the handle, whereupon said sleeve can be adjusted in relation to the rear end of the barrel and re-secured by returning the handle until it bears against said rear end.

It will be observed that the reciprocating mechanism in the casing 42 operates in an oil bath and that lubricant under pressure may be fed, when required, through the nipple 88 into the tube 54 and through same into the barrel 11 of the tool, so that the drive throughout its length and the piston in said barrel receive adequate lubrication.

It will also be observed that the disposition of the pivoted lever 68 in conjunction with the eccentric driving pin 66 on the flywheel 65 on the motor shaft 57 results in a quick-return movement of the cable 43, and that the sliding of the spherical-headed nipple 74 through the end wall of the link 71 permits the cable 43 to relax freely, thereby eliminating all mechanical stress from the point of its attachment.

What I claim and desire to secure by Letters Patent is:

1. A power-operated percussive tool comprising a reciprocable hammer, a working head secured to said tool, a work-engaging member supported in said head for reciprocable movement in axial alignment with said hammer, a transversely movable block disposed within the head between the hammer and said work-engaging member, resilient means in engagement with said block and normally retaining it in position to prevent contact of the hammer with said work-engaging member, said block and work-engaging member having cooperating means whereby the block may be moved against the tension of said resilient means to establish con-

tact of the hammer with the work-engaging member.

2. A power-operated percussive tool comprising a reciprocable hammer, a working head secured to said tool, a work-engaging member supported in said head for reciprocable movement in axial alignment with said hammer, a transversely movable block disposed within the head between the hammer and said work-engaging member, said block having an opening therethrough for permitting contact of said hammer with the work-engaging member, the forward portion of said opening being tapered, resilient means in engagement with said block and normally retaining it in position to prevent contact of the hammer with said work-engaging member, said work-engaging member being tapered at its rear end for cooperation with the opening in the block thereby to move the block against the tension of said resilient means and establish contact of the hammer with the work-engaging member when the latter is subjected to rearward pressure.

3. A power-operated percussive tool comprising a barrel, a hammer axially displaceable therein, means for reciprocating said hammer in said barrel, a hollow head secured on said barrel, a work-engaging member carried by said head, a transversely moveable block in said head provided coaxially with an aperture and a tapered socket, said work-engaging member being provided with a tapered portion to co-operate with said socket.

WILLIAM HENRY DEAN.
